UNITED STATES PATENT OFFICE

GLEN H. DINGMAN, OF CANASTOTA, NEW YORK

PROTRACTOR

Application filed May 9, 1930. Serial No. 451,046.

This invention relates to geometrical instruments and more particularly to new and useful improvements in protractors and has for its primary object to provide, in a manner as hereinafter set forth, a device of this character which will be comparatively simple in construction, strong, durable, efficient in its use and which may be manufactured at low cost.

All of the foregoing and still further objects and advantages of the invention may become apparent from a study of the following specification, taken in connection with the accompanying drawings wherein like characters of reference designate corresponding parts throughout the several views, and wherein:—

Figure 1 is a view in side elevation of a protractor constructed in accordance with this invention.

Figure 2 is a view in edge elevation thereof.

Referring to the drawings in detail, it will be seen that the reference numeral 1 designates a stationary or base arm having the straight edge 2, the stationary arm 1 is provided with a segmental recess 3 and a reduced inner end portion 4 having formed integrally thereon an ear or lug 5.

A flat segmental plate 6 is rigidly secured to the stationary or base arm 1 and to the apertured ear 5 through the medium of suitable rivets 7, said plate extending transversely across the recess 3 as clearly illustrated in Figure 1 of the drawings. The arcuate marginal portion of the segmental plate 6 is beveled, as indicated at 8 and said plate and arcuate marginal portion are graduated as indicated at 9. The numerals for the scale 40 comprise a double row which runs reversely from zero to 90 as clearly seen in Figure 1. The segmental plate 6 is further provided with an arcuate slot 10.

A swinging arm 11 provided with a straight edge 12 has formed integrally on one end a substantially circular lug or extension 13 which is rotatably seated in the recess 3 and is disposed against one side of the segmental plate 6 to which the same is rotatably secured through the medium of a suitable

pivot pin 14. The inner end of the swinging arm 11 is provided with a recess 15 for the reception of the apertured ear or lug 5 on the extension 4 when the said swinging arm 11 is moved to open position. Within the open position, the inner end of the swinging arm 11 is seated on the extension portion 4 of the stationary arm 1.

A threaded screw 16 is rigidly mounted on the swinging arm 11 and projects therefrom through the arcuate slot 10 in the segmental plate 6, said screw adapted to travel through said slot upon swinging movement of the arm 11. A thumb nut 17 is threaded on the screw 16 for engagement with the adjacent space of the segmental plate 6 for frictionally securing the swinging arm 11 in adjusted position. The arm 11 is further provided with an indicating arrow 18 which coacts with the scale 9 to facilitate the use of the instrument.

As will be obvious, when it is desired to adjust the instrument the thumb nut 17 is loosened and the arm 11 is swung to the desired angle, after which the thumb nut 17 is again tightened.

As before stated, when the swinging arm 11 is moved to the limit of its outward swinging movement the inner end thereof abuts the inner edge of the reduced portion 4 of the stationary arm 1 and the apertured ear or lug 5 is disposed snugly in the recess 15 in the inner end of said swinging arm 11. In this manner an exceedingly strong and durable instrument is provided which is extremely simple in construction and efficient in its use.

While the arms 1 and 11 and the segmental graduated plate 6 may be formed of any suitable material, the same are preferably made of a light transparent material such as celluloid.

It is believed that the many advantages of a protractor constructed in accordance with this invention will be readily understood, and although the preferred embodiment of the invention is as illustrated and described, it is to be understood that changes in the details of construction may be had which will fall within the scope of the invention as claimed.

What is claimed is:—

1. A protractor of the character described

comprising a stationary arm formed to provide a straight edge and having a reduced end portion, said arm being further provided with an arcuate recess at the point where the reduced portion merges therewith, an integral apertured ear projecting laterally from the reduced end portion, a flat, segmental plate rigidly secured to the stationary arm and to the apertured ear, said plate being disposed across the recess, a swingable arm having an integral substantially circular extension on one end portion, said extension being rotatably seated in the recess of the stationary arm, a pivot pin extending through the segmental plate and the substantially circular extension for swingably mounting the second named arm on the segmental plate, one end of the swingable arm being engageable with the inner side edge of the reduced portion of the stationary arm and having a recess formed therein for the reception of the apertured ear when said swingable arm is in open position.

2. A protractor of the character described comprising a stationary arm formed to provide a straight edge and having a reduced end portion, said stationary arm being further provided with an arcuate recess formed therein at the point where the reduced end portion merges therewith, an integral ear projecting at right angles from the reduced portion, a flat segmental plate rigidly secured to the stationary arm and to the ear, said plate extending across the arcuate recess and having an arcuate slot therein, said plate being further provided with a graduated beveled arcuate marginal portion, a swingable arm having a substantially circular extension formed laterally on one end portion, said extension being pivotally connected to the segmental plate on one side thereof and rotatably seated in the arcuate recess of the stationary arm, a threaded screw anchored in the swingable arm and projecting therefrom through the slot in the segmental plate for movement therethrough upon swinging movement of said swingable arm, a thumb nut threaded on the screw for engagement with the segmental plate in a manner to frictionally secure the swingable arm in adjusted position, the pivoted end of the swingable arm being adapted to abut the adjacent longitudinal side edge of the reduced portion of the stationary arm when in open position and having a recess therein for the reception of the ear.

55 In testimony whereof I affix my signature.
GLEN H. DINGMAN.
